Filed Dec. 12, 1957, Ser. No. 702,340

9 Claims. (Cl. 313—92)

The present invention relates to cathode ray tubes and more particularly to a cathode-ray tube capable of color display employing a layered phosphor target screen.

In the prior art, attempts have been made to produce color kinescopes employing a single electron gun wherein a plurality of phosphors capable of emitting light of different colors are settled on the target screens in discrete layers. The layer to be excited is determined by varying the velocity of the electrons which are caused to strike the composite target screen. By varying the velocity of the electrons, the depth of penetration of the electrons into the target screen may be varied. Manifestly, to effect the maximum degree of penetration, the application of extremely high voltages would be of paramount necessity during which time correspondingly high voltages would be required to effect the desired scanning of the electron beam across the target screen. In conjunction with such tube, rather extensive electronic circuitry may be required for effecting switching of the beam between colors.

It is an object of the present invention to produce a cathode ray tube capable of providing color display which is simple in construction and consumes a minimum amount of electrical energy in effecting color selection or switching.

It is a particular object of the invention to provide a cathode ray tube which is capable of providing color displays which are operative to provide a display indicative of incoming saturation, hue and brightness signals.

The instant invention in one embodiment comprises a target comprised of a control layer and a plurality of phosphor layers disposed in superposed relation, each phosphor layer being capable of emitting a different color light upon electron excitation. In a preferred embodiment, a first electron beam of insufficient energy to penetrate the control layer is delivered into registration with the target. This beam is operative to vary the potential on the various portions of the impinged target in accordance with the energizing control signals which are fed to the electron source. A second electron beam is delivered into registration with the target and will penetrate therein in a degree determined by the potential impressed thereon following registration of the first mentioned beam therewith.

This invention will be clearly understood from reading the following detailed description when taken in view of the following drawings in which:

Figure 1 is a front elevational view partially in section of a cathode ray tube employing the instant invention;

Figure 2 is a sectional view of the tube illustrated in Figure 1 taken along line 2—2;

Figure 3 is an end view of a modification of cathode ray tube shown in Figures 1 and 2;

Figure 4 is a view similar to Figure 1 showing another modification of the invention shown in Figures 1 and 2 wherein the electrons are initially directed along a marginal edge of the target screen and illustrates the so-called Aiken double bend tube.

2

Figure 5 is a sectional view of the tube taken along line 5—5 of Figure 4; and

Figure 6 is a schematic illustration of a control circuit for energizing the various embodiments.

Figures 1 and 2 show a cathode ray tube of the Aiken type wherein there is a relatively flat or shallow envelope 10 adapted to completely house the internal components of the device. A pair of electron guns 12 and 14 adapted to deliver electron beams 16 and 18 respectively is disposed in spaced relation with respect to a marginal edge of a composite target screen S. The electron guns are provided with conventional electrostatic deflection plates 20 and 22 respectively. However in the event electromagnetic deflection is deemed desirable, magnetic yokes may be employed to effect the desired scanning control of the electron beams.

The target screen S is comprised of a supporting plate 24 and a plurality of superposed phosphor material layers 26, 28 and 30, each of the phosphor layers being capable of emitting light of different colors upon excitation by an impinging beam of electrons. The arrangement of the phosphor layers may be such that layer 26 will give off green light; layer 28, red light; and layer 30, blue light. Also there is provided a control layer 31 which is transparent to electrons of a predetermined velocity and which also may be optically transparent. In a preferred embodiment, the successive layers of the phosphors are made progressively thicker to provide improved energy distribution and a more pure color display. The screen is not, of course, limited to such arrangement.

It will be noted that a plurality of so-called vertical deflection electrodes 32 are disposed in spaced relation from the composite target screen S. Each of the deflection electrodes 32 is electrically coupled to an electric generator preferably situated outside the tube envelope. The deflection electrodes 32 may be formed of an electrically conducting material which is optically transparent such as for example conducting glass. Manifestly by forming the deflection electrodes 32 of a transparent material, any display presented on the target screen S may be readily viewed from each surface thereof. The composition target screen S and the vertical deflection electrodes 32 may be referred to as the secondary or high voltage section of the tube.

The instant invention is operative to achieve color display as well as in certain applications, black and white displays. Color presentations are effected by the principle of selected penetration of an electron beam into the target screen S, comprised of the superposed layers 26, 28, 30 of phosphor material which when individually energized will give off green, red and blue light respectively. The penetration of the impinging electron beams into the target screen S is varied by varying the potential of the different target areas and particularly the potential of the different areas of the control layer 31.

More specifically, it is proposed in the instant arrangement to employ two electron guns 12 and 14 which are operative to deliver electron beams 16 and 18 respectively. The electron gun 12 is controlled by the color component of the transmitted signal and the electron gun 14 is controlled by the brightness component of the transmitted signal.

In operation, the beams 16 and 18 are delivered along a path between the target screen S and the array of vertical deflection elements 32, the position of the initial beam paths adjacent the vertical deflection elements 32 being controlled by the energization of the deflection plates 20, 22 of the respective electron guns 12 and 14. It will be appreciated by those skilled in the art that the electron beams 16 and 18 may be effectively caused to scan the target screen by varying the voltages impressed on the deflection plates 20 and 22 and the deflection

plates 32 in a synchronized manner. In the event the instant tube were employed for the reception of conventional television information, the signals impressed on the deflection plates 20 and 22 would be the horizontal oscillator output signals at 15,750 cycles per second, and the vertical oscillator signals would be applied to a control circuit which in turn applies energizing potentials to the vertical deflection electrodes 32 in a progressive overlapping manner.

If the deflection electrodes 32 are initially all maintained in the order of 15 kv. and the target screen is maintained at a like potential, a field-free region will be created thus allowing the electron beams to travel therein unaffected. With the application of the horizontal sweep signal to the deflection plates 20, 22 the electron beams are initially delivered adjacent the left hand margin of the target and the vertical deflection electrodes, and the voltage on the upper deflection electrodes is lowered to bend same into registration with the upper left hand corner of the target. With continued application of the horizontal sweep signal to the deflection plates 20, 22 the beam sweeps the zone adjacent the target, and the end thereof traces a linear path adjacent the upper marginal edge of the target. As the voltage is progressively lowered on the successive deflection electrodes 32, the successive lines of the raster are traced on the target screen S. Each of the electron guns and associated primary sets are operated at different potentials, as more fully described hereinafter.

As mentioned hereinabove, a color display is achieved by varying the penetration of the electrons into the target screen S. In a first embodiment the electron guns 12 and 14 are controlled by different control signals, the gun 12 being controlled by the hue or color component of the transmitted signal, while the gun 14 is controlled by the brightness signal. In practice, the color selecting or hue beam 16 emanating from the electron gun 12 is adapted to sweep the target screen slightly in advance of the brightness beam 18 which emanates from the electron gun 14. Also, since the beams initially travel along paths differently spaced from deflection electrodes 32, a corresponding adjustment is made in the velocities of the respective beams 16, 18 to insure registration of the beams with identical linear paths for each of the successive traces.

Thus the color selecting or hue beam 16 is composed of electrons which have traversed a voltage gradient insufficient to allow the electrons to penetrate the control layer 31, and the intensity of the beam 16 will determine the value of the potential on the target screen at each localized area of impingement. It is apparent that variation of the beam value as it impinges with successive areas in its sweep across the screen will effect a corresponding variation of the value of the charge on the different incremental screen areas.

It is well known that an electron of a given velocity will penetrate a phosphor layer a given distance and can be made to give up the majority of its energy in that layer. Accordingly, with the cathode voltage of the electron gun 12 operated at +10 kv. and the composite target screen operated at 20 kv., the color beam 16 will not have sufficient velocity to penetrate the first layer 31 of the target screen S. However, as mentioned above, the beam 16 will tend to discharge the areas on which it impinges and thereby vary the voltage of incremental areas of the target screen S. The value of the voltage at each incremental area will determine the degree of penetration of the layers by the brightness beam 18 which emanates from the electron gun 14, and which scans the target screen S slightly behind the color beam 16.

In the event that the color desired at an area is green, the color beam 16 is caused to discharge the desired area of the target screen S a minimum amount and therefore the brightness beam 18 will be caused to penetrate the

non-fluorescent layer 31, the phosphor layers 30 and 28, and finally come to rest in the layer 26 which will emit green light. It is apparent that the smaller the charge on a given incremental area of the target screen S following registration of the color beam 16, the less the amount of penetration which can be achieved by the brightness beam 18. Thus color selection or hue for a particular area is determined by controlling the intensity of the color selection beam 16 at the time of registration with such area.

Prior to the initiation of each raster trace, the various layers are recharged by any one of a number of acceptable methods. In one preferred arrangement, recharging of the phosphor layers is effected by the application of leakage currents over the conductive layer 31. Other methods will be readily obvious to parties skilled in the art.

The control circuit for the thin tube is set forth in the schematic showing of Figure 6, wherein a conventional color receiver is connected to effect application of the hue and brightness signals over conductors 62, 70 to electron guns 12, 14, respectively in the manner of the previously disclosure. Delay circuit 72 introduces the necessary time differential between the sweeping of the screen by the respective beams 16 and 18 in their provision of the color rasters. The operation of the system to provide a color display will be obvious from the foregoing disclosure.

In a second embodiment, the color system is adapted to additionally respond to saturation signals, such arrangement being also schematically illustrated at Figure 6. Briefly, the saturation signal detected by receiver 60 is applied over conductor 64 to a high frequency modulation circuit (approximately one magacycle in value) the output of which is connected over capacitor 67 and conductor 68 to the grid (or cathode) of the hue gun 12. The signal output of the modulator unit 66 to the hue gun 12 is commensurate with the value of the saturation signal applied to the input of modulator 66 by receiver 60.

In operation the hue beam is controlled to sweep across the control layer 31 in the manner previously described to condition the successive incremental areas of the target to different voltages in preparation for the registration of the brightness beam with such areas. The brightness beam 18 in its sweep across the target closely behind the hue beam penetrates the control layer to the particular color layer indicated by the value of the charge on the control layer at such area. Thus the display of a fully saturated red (the second layer 28 in the present example) by an area is effected by controlling the hue beam to discharge the area to a value sufficiently low to prevent penetration of the brightness beam beyond the second layer. The brightness of the fully saturated red color is determined by the intensity of the brightness beam.

With receipt of the incoming saturation signal indicating a diluted red signal, a saturation signal is applied to the modulator unit 64 which is proportional to the degree of dilution desired, and the modulator unit 64 is responsive to couple a proportionate signal over capacitor 67 and conductor 68 to the grid (or cathode) of the hue gun 12 to modulate the output thereof by a corresponding value. With the application of the modulation frequency to the gun 12, the potential in closely successive incremental intervals on the control layer 31 adjacent the initial point of color selection will be successively varied in a manner related to the successive value of the beam. The successive intervals of the area thus conditioned are so close as to appear to the observer as a single dot, and as a result of the difference of potential established on these successively adjacent intervals, the brightness beam in its registration therewith will move through the three successive phosphor

layers in rapid succession to obtain the color white, whereby the color selected by the hue beam will be diluted by an amount of white light which is commensurate with the value of the incoming saturation signal.

In such embodiment, therefore, the value of the incoming brightness signal controls the value of the brightness beam and the resolution and picture brightness; the incoming hue signal controls the intensity of the hue beam and the color to be selected; and the incoming saturation signal controls the degree of steady high frequency modulation of the hue beam, and therefore the dilution of the selected color with white light.

Figure 3 shows a modification of the cathode ray tube illustrated in Figures 1 and 2, wherein the target screen S is identical with that illustrated in the earlier figures with an additional phosphor layer 34 disposed on the side opposite the layered phosphors. The layer 34 is operative to be used in the presentation of the conventional black and white displays. For purposes of simplification prime numerals are used to denote the elements of the tube which are similar to those shown and described in connection with Figures 1 and 2.

A second set of vertical deflection electrodes 36, similar to electrodes 32, are disposed in adjacent spaced relation with respect to the layer 34. The electrodes 36 are formed of electrically conductive optically transparent material such as for example conducting glass.

An electron gun 38 is disposed in the same relative position with respect to the composite target screen S as the electron guns 12' and 14' and is operative to deliver an electron beam 40 along a path which lies between the phosphor layer 34 and the set of deflection electrodes 36. A pair of conventional electrostatic deflection plates 42 are employed to effect the desired directional control of the electron beam 40 in a plane substantially parallel to the layer 34. The beam 40 may be deflected toward and into impingement with the target by suitably energizing the deflection electrodes 36 in the manner described hereinabove with respect to the similar deflection electrodes 32 of Figures 1 and 2. 40 Further it will be appreciated that a raster may be accomplished through proper synchronization between the energization of the deflection plates 42 and the deflection electrodes 36.

It will be obvious to those skilled in the art that the cathode ray tube shown in Figure 3 is capable of achieving separate black and white display.

The device illustrated in Figures 1, 2, and 3 uses a deflection principle known in the art as the Aiken single bend deflection method. However, it must be understood that the invention may also be employed in connection with the Aiken double bend deflection principle. The cathode ray tube illustrated in Figure 4 incorporates the instant invention and is in many respects similar to the arrangement shown in Figures 1 and 2 but employs the advantageous inherent focussing principles of the Aiken double bend deflection method. In the cathode ray tubes employing this type deflection arrangement the internal components are divided generally into three major sections: primary, transition, and secondary or high voltage. The primary section includes a pair of electron guns 50 and 50', capable of delivering an electron beam 52 and 52' respectively, two linear arrays of horizontal deflection electrodes 54 and 54' and a pair of slotted electrodes 56 and 56'. The transition section includes two pairs of focussing and accelerating electrodes 58 and 58'. The secondary or high voltage section includes the composite target screen S and a plurality of vertical deflection electrodes 32'. The secondary section of the tube shown in Figures 4 and 5 is identical with that shown in Figures 1 and 2 and accordingly, prime reference numerals are employed to denote similar elements.

In operation, the electron gun 50 which delivers the beam 52 is controlled by the color and saturation components of the transmitted signal, while the electron gun

50' which delivers the beam 52' is controlled by the brightness component of the transmitted signal. The color beam 52 is controlled to scan the target slightly in advance of the brightness beam 52' and such is accomplished in this embodiment by applying energizing signals to the horizontal deflection electrodes 54 slightly in advance of the energizing potentials applied to the deflection electrodes 54'. The desired deflection of the electron beam 52 is accomplished by maintaining all the electrodes 10 54 at a negative potential with respect to the beam 52, and selectively driving them in a positive direction toward the potential of the associated slotted electrode 56. Accordingly, it will be appreciated that if the electrode 54 closest to the electron gun 50 is negative with respect to the beam 52, the beam will be deflected upwardly between the focussing and accelerating electrodes 58 and thence into a field-free zone within the secondary section. This field-free zone is established by maintaining the target screen S' and the vertical deflection electrodes 32' at substantially the same potential. The beam 52 will therefore travel unaffected until such time as the voltage on one or more of the electrodes 32' is caused to be lowered a degree sufficient to cause the beam to be deflected toward and impinge on the target screen S. In order to effect movement of the beam 52 across the face of the target screen S', the horizontal deflection electrode 54 which is effecting the first bend in the beam is driven to substantially the same potential as that on the slotted electrode 56 thus creating a field-free region between that deflection electrode 54 and the slotted electrode 56 allowing the beam 52 to travel therethrough until it "sees" the negative or repelling field established by the next adjacent electrode 54. To assure a linear deflection of the beam, the deflection electrodes 54 as well as the deflection electrodes 32' are energized in an overlapping manner. That is, prior to the instant the first energized electrode has reached its full charged or discharged state (depending upon which electrodes are concerned) the charge or discharge of the next adjacent electrode is commenced.

In the preferred embodiment the primary associated with the brightness gun 50' is operated with the cathode of the associated primary section 54' at zero potential, and the color gun 50 is operated with the cathode and primary at approximately 10 kv. so that the beam 52 delivered thereby will not fall through enough voltage to provide sufficient energy to cause same to pass through the control layer 31'. It is apparent that the two primaries may be swept by the same sweep generator by connecting like deflection plates 54, 54' in the two primaries together through suitable capacitor members, and differential in the sweeping of the target by the two beams may be effected by the use of a suitable delay network 72 in the control circuit for the deflection plates associated with the brightness gun 50'. If preferred, the low velocity hue beam can be made to precede the brightness beam when sweeping by physically placing the primary associated with gun 50 ahead of the primary associated with the brightness gun 50'. Alternatively, the differential can be introduced by changing the cathode grid voltage of the gun with respect to its slotted accelerator.

Other methods will be apparent to parties skilled in the art.

In order to effect movement of the beam 52 down the face of the target screen S the vertical deflection electrodes 32' are selectively energized in an overlapping manner such that they establish a deflecting force sufficient to effect a second bend in the beam 52 so as to cause it to be deflected toward and into impingement with the target screen S at successive points down the surface thereof. Manifestly, by properly synchronizing the energization of the horizontal deflection electrodes 54 and the vertical deflection electrodes 32' a complete raster may be obtained.

As explained in connection with Figures 1 and 2, the color beam is operative to change the potential of vari-

ous areas of the target screen S in accordance with the received color signal, and the various areas, being charged differently will correspondingly vary the depth of penetration of the brightness beam 52' which follows closely behind the color beam 52. The saturation signal in turn effects time sharing of the brightness beam with the different phosphor layers by suitable modulations of the hue beam. The brightness beam 52' and color beam 52 are deflected in the manner above described and accordingly, it is not believed that a further description is necessary for a complete understanding of the invention.

According to the provisions of the patent statutes, the principles and mode of operation of the invention have been explained, illustrated and described in what is considered to be the best embodiments. However, it is to be understood that, within the scope of the appended claims, the invention may be practiced otherwise than specifically illustrated and described.

What is claimed is:

1. In a cathode ray tube for use in the presentation of color displays, a target comprised of a plurality of phosphor layers and a control layer disposed in superposed layered relation with each other, each phosphor layer being capable of emitting a different color with energization thereof, color selection means for delivering a first electron beam for registration with an incremental area of said target control layer to change the potential thereof a predetermined amount consistent with the particular phosphor layer to be energized, and brightness control means including means for providing a second beam for registration with said incremental area thereafter and the penetration thereof through the multiple layers to the one of the phosphor layer indicated by the potential condition established by said first beam on the corresponding incremental area of the target control layer to effect the energization of said one color layer thereof.

2. In a cathode ray tube for use in the presentation of color displays responsive to the receipt of different color selection signals, a target comprised of a plurality of phosphor layers and a control layer disposed in superposed relation with each other, each phosphor layer being capable of emitting a different color with energization thereof, color selection means for providing a first electron beam for registration with an incremental area of said target control layer to change the potential thereof a predetermined amount consistent with the particular phosphor layer to be energized, means for applying the incoming color signals to said color selection means to control the value of the potential change effected by said first electron beam, and brightness control means including means for providing a second beam for registration with said incremental area subsequent to said first beam to penetrate the plurality of layers to the one of the color layers indicated by the potential condition previously established by said first beam on said control layer to effect the energization of said one color layer thereof.

3. In a cathode ray tube for use in the presentation of color displays, a target comprised of a plurality of phosphor layers and a control layer disposed in superposed relation, each phosphor layer being capable of emitting a different color with energization thereof, color selection means including means for delivering a first electron beam for registration with an incremental area of said target control layer to change the potential thereof a predetermined amount consistent with the particular phosphor layer to be energized, brightness control means including means for providing a modulated second beam for registration with said incremental area, and means for controlling said second beam to strike said incremental areas subsequent to said first beam to thereby effect penetration of the beam through said phosphor layers to the one of the color layers indicated by the potential condition previously established by said first beam and to provide a brightness output of a value determined by the

degree of modulation of the beam at its time of registration therewith.

4. In a cathode ray tube for use in the presentation of color displays responsive to the receipt of different color selection and brightness signals, a target comprised of a plurality of phosphor layers and a non-foraminous control layer disposed in superposed contacting relation with each other, each phosphor layer being capable of emitting a different color with energization thereof, color selection means including means for delivering a first electron beam for registration with an incremental area of said target control layer to change the potential thereof a predetermined amount consistent with the particular color signal received, brightness control means including means for providing a second beam for registration with said incremental area subsequent to said first beam to thereby effect penetration of said second beam through the control layer and the superposed phosphor layers to the one of the color layers indicated by the potential condition previously established by said first beam, and means for modulating the intensity of the second beam in accordance with the value of the received brightness signal.

5. In a cathode ray tube for use in the presentation of color displays, a target comprised of a plurality of phosphor layers and a control layer disposed in superposed relation, each phosphor layer being capable of emitting a different color with energization thereof, color selection means including means for providing a first electron beam, deflection means for selectively directing said beam into registration with the different incremental areas, of said target control layer independent of each other to change the potential thereof a predetermined amount consistent with the particular one of the phosphor layers to be energized at each area, and brightness control means including means for providing a second beam for deflection by said deflection means into registration with each incremental area independent of the other incremental areas subsequent to registration of said first beam therewith to effect energization of the color indicated by the potential condition by the control layer as established by said first beam.

6. In a cathode ray tube for use in the presentation of color displays, a target comprised of a plurality of phosphor layers and a control layer disposed in superposed relation, each phosphor layer being capable of emitting a different color with energization thereof, deflection means disposed in adjacent spaced relation with said target, color selection means including means for delivering a first electron beam between said target and said deflection means for selective deflection into registration with an incremental area of said target control layer to change the potential thereof a predetermined amount consistent with the particular phosphor layer to be energized, and brightness control means including means for delivering a second beam between said deflection means and said target for selective deflection into registration with said incremental area subsequent to said first beam to thereby effect energization of the color indicated by the potential condition established on the control layer by said first beam.

7. In a cathode ray tube for use in the presentation of color displays, a target comprised of a plurality of phosphor layers and a control layer disposed in superposed relation, said control layer being comprised of a non-luminescent material and each successive phosphor layer in the target relative to the direction of travel of the beam being of a progressively increased thickness and capable of emitting a different color with the energization thereof.

8. In a cathode ray tube for use in the presentation of color displays, a target comprised of a plurality of phosphor layers and a control layer disposed in superposed relation, each phosphor layer being capable of emitting a different color with energization thereof, color selection means for delivering a first electron beam for

registration with an incremental area of said target to change the potential thereof a predetermined amount consistent with the particular phosphor layer to be energized, brightness control means including means for providing a second beam for registration with said incremental area thereafter to thereby effect energization of the one of the color layers indicated by the potential condition established on said target by said first beam, and saturation control means for controlling said first beam to condition said target to effect time sharing of the second beam between the different phosphor layers and thereby dilute the selected color.

9. In a cathode ray tube for use in the presentation of color displays in accordance with the information contained in incoming hue, brightness, saturation signals, a target comprised of a plurality of phosphor layers and a control layer disposed in superposed relation, each phosphor layer being capable of emitting a different color with energization thereof, color selection means for delivering a first electron beam of insufficient energy to penetrate the control layer for registration with an incremental area of said target control layer to change the potential thereof a predetermined amount consistent with

the value of the incoming line signal, brightness control means including means for providing a second beam of an intensity related to the incoming brightness signal for registration with said incremental area subsequent to registration of said first beam to thereby effect energization of the one of the color layers indicated by the potential condition established on the control layer by said first beam, and saturation control means for controlling said first beam to condition said control layer to share the second beam between the different phosphor layers in relation to the value of the incoming saturation signal.
